MACHINE FOR WORKING UPPERS
OVER LASTS

Frank Coleman Choice, Leicester, England, assignor to United Shoe Machinery Corporation, Flemington, N. J., a corporation of New Jersey

Application January 29, 1948, Serial No. 5,147
In Great Britain February 18, 1947

26 Claims. (Cl. 12—7.8)

1

This invention relates to improvements in machines for working uppers over lasts and particularly, but not exclusively, to machines for lasting the foreparts of stitchdown shoes.

The invention will be herein illustrated and described as embodied in a machine of the type disclosed in an application for Letters Patent of the United States Serial No. 736,300, filed March 21, 1947, in the names of Choice and James, and in Letters Patent of the United States No. 2,152,855, granted April 4, 1939, upon the application of Ricks, Boothroyd, and James.

Machines of this type comprise a shoe support inclined upwardly and away from the operator and adapted to receive and support the forepart of a stitchdown shoe with its bottom face downward and with its toe pointing away from the operator. Said machines also comprise a toe-end gripper and two side grippers operable by power-actuated means for gripping and tensioning the toe portion of a shoe upper and a pair of wipers movable from a retracted position to an operative position from which they are moved heightwise of the shoe to wipe the upper toward the sole after it has been tensioned and pulled down tightly to the last by the three grippers. The machine described in the above-mentioned application further comprises a pair of adjustable shoe-positioning and upper-controlling fingers which engage side portions of the last at localities lying between the toe-end gripper and the two side grippers in order correctly to position the last with the upper thereon relatively to the wipers for their operation on the upper. These fingers support portions of the upper between the grippers during the tensioning operation thereon, thereby assisting in preventing wrinkles in those portions of the upper, and they cooperate with the wipers toward the end of their downward wiping movement to clamp the marginal portion of the upper between the fingers and the wipers and thus act as retarding devices for controlling the upper prior to its being worked into the angle between the sole margin and the side of the last by advancing and closing movements of the wipers.

The shoe support of the machine comprises two parts, a central part which is adapted to support the last and shoe during the upper-tensioning and wiping operations of the machine and an outer sole-margin-engaging part which is movable heightwise relatively to the central part under power operation to press the marginal portion of the sole and the outwardly extending flange of the upper upwardly against the under

2

surface of the wipers to cause a semi-permanent set to be imparted to the outwardly extending flange of the upper. The uppers of stitchdown shoes differ as to the materials constituting the uppers as well as to the general stoutness of the uppers and the amounts of material available to be acted on by the grippers and wipers of a machine constructed as above referred to. These different conditions render difficult the insertion of the upper margins of successive shoes between the gripper jaws since the jaws of the grippers in their open condition do not, in the prior machine, offer as large an upper-receiving space between them as would be most suitable to receive the upper margins which are not at that time outspread in a fairly flat condition.

It has been found also that the materials constituting the toe portion of the upper often include a toe stiffener which is in a somewhat adhesive condition at the time when the shoe is presented to the machine. The toe stiffener therefore adheres to the lower jaws of the grippers after the grippers are opened to release the upper to allow the shoe to be removed from the machine. This adhesion between the stiffener and the gripper jaws tends to pull the upper out of its conformed relation to the last as the operator removes the shoe from the machine. Moreover, the toe-end gripper of a machine constructed as above referred to receives a movement in a direction extending lengthwise of the last at a relatively early stage in its upper-pulling movement, and this sometimes gives rise to a tendency to disturb the position of the last in the machine.

Important objects of the present invention are to provide a machine of the type disclosed in the above-mentioned application so arranged as to overcome the defects referred to.

Other objects of the invention are to improve the cooperation of various instrumentalities of a machine constructed generally as disclosed in said application.

With the above and other objects in view, the invention includes novel gripper-operating mechanism, a novel arrangement for forcibly separating upper material from the grippers of the machine after the grippers have opened to release the upper, and modified means for operating a heel abutment and shoe-positioning fingers of the machine. To facilitate presentation of the margins of a shoe upper between the jaws of the grippers, the machine includes an organization which causes the jaws of the three grippers to be opened apart to an unusually wide angle when in their upper-margin-receiving condition and

includes auxiliary jaw-closing mechanism which operates automatically after the upper margin has been placed between the jaws and, after the machine has been started into power operation, to swing the upper jaw of each gripper so far toward its cooperating jaw that a power-operated, jaw-closing and moving means for each gripper may become effective to move the upper jaw into gripping engagement with the upper and then move the gripper bodily in a direction to tension the upper.

To forcibly separate from the lower jaws of the side grippers any material that may adhere to the lower jaw, the illustrated machine includes in each side gripper a stripping device having upper-stripping prongs which lie in recesses in the upper-engaging face of the lower jaw when the grippers are closed upon the upper and which are automatically raised from said recesses as the open grippers are returned to their initial raised position to lift any material still overlying the lower jaw away from engagement therewith.

The illustrated machine includes a mechanism which operates independently of the mechanism which imparts the upper-tensioning movement to the gripper for causing the gripper to impart a foredraw or lengthwise pull to the toe end of the upper after a considerable portion of the upper-tensioning movement has taken place.

In the illustrated machine, a heel-end abutment is caused to move into shoe-supporting engagement with the upper only after the side grippers have commenced to tension the upper, thereby reducing the tendency for the forward thrust of the abutment to displace the shoe from its proper position in the machine.

In the illustrated machine, the shoe-positioning fingers have their return to operative position delayed, the fingers being held in their retracted inoperative position by a latch device which is released to allow them to move to operative position substantially when other parts of the machine reach their final position of rest. This delay in the movement of the fingers provides more time for the operator to remove the shoe from the machine without danger of its being fouled by the shoe-positioning fingers.

These and other features of the invention will appear more fully from the following description when read in connection with the accompanying drawings and will be pointed out in the appended claims.

In the drawings,

Fig. 1 is a side elevation of a machine embodying the present invention with part of the outer casing broken away;

Fig. 2 is a side elevation of parts shown in Fig. 1 with the wipers in their forward or operative position and with the toe-positioning fingers in their inoperative position;

Fig. 3 is a detail view of the end of one of the shoe-positioning fingers;

Fig. 4 is a plan view of the shoe support, grippers and shoe-positioning fingers and shows the means by which the adjustment of the shoe-positioning fingers is indicated;

Fig. 5 is a front elevation of the mechanism for raising the central portion of the work support;

Fig. 6 is a side elevation, partly in section, of the toe gripper including its overdraw mechanism;

Fig. 9 is a view of one of the side grippers with its jaws in fully open position;

Fig. 10 is a side elevation of the toe gripper in open position;

Fig. 11 is a similar view showing the jaws in partly closed position;

Fig. 12 is a front view of the main shaft and cams by which the machine is operated; and

Fig. 13 is a cam chart indicating the relative timing of the various parts.

Like the machine described in said application, the illustrated machine is a twin machine only one side of which is herein shown and described, it being understood that the other side is of similar construction except that it is adapted for treating a shoe for the other foot. The machine comprises a base casting 40 and a head casting 42, a shoe-supporting device 44, a toe-end gripper 46, a pair of side grippers 48, 50, a pair of wipers 52, a vamp-pressing member 54, a heel-end abutment 56, a pair of toe-positioning fingers 58, and means for operating these instrumentalities which may be substantially like the corresponding parts of the machine disclosed in the above-mentioned application except as will be hereinafter pointed out. The machine has means for actuating the three grippers to seize and pull the upper. The three grippers and the means for operating them are substantially alike except as will be herein-after explained and the toe gripper will be first described, it being understood that the similar parts of the side grippers are designated by the same characters. The toe gripper (Figs. 6 and 7) comprises a lower jaw 60 secured at 61 to a gripper casing 62 the lower portion of which is formed as a sleeve 63 through which a gripper-operating rod 64 extends. Surrounding the lower portion of the gripper casing 62 is a sleeve 65 which is pivoted at 66 to a bracket 67 secured at 68 to a supporting post 69.

An upper jaw 70 is pivoted at 71 to ears on the casing 62. In the illustrated machine the upper jaws of all three grippers are arranged to open relatively to the lower jaws to such an extent that the planes of the upper-engaging surfaces of the upper jaws lie at some 50° to the plane of the lower jaw, as shown in Fig. 10, in the case of the toe gripper. The plane of the lower jaw extends inwardly and upwardly at an angle of about 20° to the plane of the bottom of the shoe supported by the shoe support 44 so that the upper-engaging surface of the upper jaw lies, when the gripper is opened, at an angle of about 70° to the plane of the shoe bottom. The fact that the upper jaw extends upwardly at such a relatively steep angle enables the operator easily to insert the margin of the upper between the jaws as he positions the shoe in the machine. The angular disposition of the lower jaws in relation to the plane of the shoe bottom is such that the lower jaw lies roughly parallel to the position of the marginal portion of the upper material at the time the shoe is presented to the machine, that is, loosely outwardly and downwardly from the last. The movement of each of the two side grippers as they tension the upper takes place in such a direction that the upper margin is not deflected to any substantial extent.

During power operation of the machine, the upper gripper jaws of the three grippers are closed in two stages. During the first stage, the upper jaws are moved about their pivots 71 until they occupy positions relative to the lower jaws of

about 25° (Fig. 11). This movement of the upper jaws of the grippers in the illustrated machine is brought about by auxiliary gripper-actuating mechanism which will now be described.

Each gripper jaw 70 has a tail portion 72 projecting beyond the pivot 71 for the jaw. Arranged to engage a lower surface 74 of the tail portion 72 is a roll 75 on the upper end of an arm 76. The arm is freely pivoted on a stud 78 extending between a pair of parallel side plates 80 which lie one on each side of the tail portion 72 of the upper jaw these plates being pivoted on the stud 71. The plates 80 are connected together at their outer upper end portions by means of a spacing member 82 (Fig. 7) extending between the plates. The arms 76 are arranged to be swung in the gripper-closing direction about their pivots 78 to cause the roll 75 to ride along the under surface of the tail portion 72 of the upper jaws until the arms 76 lie at right angles to said surfaces, further movement of the arms in this direction being arrested by engagement with the separating members 82.

The gripping faces of the upper jaws will now be at an angle of about 25° to the lower jaws (Fig. 11). The downward movement of each upper jaw takes place against the action of a tension spring 84 extending between a pin on the upper jaw and an ear 87 on the separating member 82, that is, the upper jaw is biased to open position. Since, in the partially closed position of the jaws, the arms 76 have been moved clockwise just beyond a position at right angles to the under surfaces 74 of the tail portions of the jaws, these jaws and the side plates 80 thereof act as one member when the plates 80 are swung about the pivot studs 71 by a gripper-actuating mechanism to effect final closing of the jaws.

To effect the swinging movement of the arms 76, each arm has a lug 86 extending inwardly and downwardly therefrom, the lug having an under surface arranged to be engaged by the end of a rod 88 which extends upwardly and somewhat inwardly from a pin 90 (Fig. 6) by which its lower end is pivoted between walls of a deep groove cut in the arcuate peripheral surface of an actuating member 92. The member 92 is pivoted on a pin 94 which is at the center of the arcuate periphery of the member. Pivotal movement of the member 92 acts as a crank to move the rod 88 endwise and move the arm 76 into the position shown in Fig. 7. The pivot 94 is carried by a bracket 96 which is secured to a block 98 extending outwardly from the lower end portion of the gripper casing 62, the lower end portion of the casing extending somewhat below the sleeve 65 in which the casing slides.

The upper end portion of each rod 88 extends upwardly through a hole in a block 99 connected between the lower portions of the side plates 80, the holes being large enough to permit swinging movement of the side plates about the studs 71 during the final closing movement of the grippers. To rock the arcuate members 92 of the three grippers about their pins 94, Bowden cables 100 are provided, one for each member 92. One end portion of each cable is secured in a pin 102 lying near the periphery of the member 92 and extends therefrom downwardly in a circumferential groove formed in the member. A pull on the cables 100 is effective to rock the associated member 92 in such a direction as to raise the rods 88 which, by engaging the lugs 86, swing the arms 76 to move the upper jaws 70 to their partially closed position, as shown in Fig. 11. Tension springs 106

are provided for each member 92, each spring being connected between a pin secured in the arcuate member and a pin 107 secured in the bracket 96 and being effective to return the member to its initial position with the rod 88 lowered. The cables 100 pass downwardly through heightwise extending bores in the blocks 98, the lower end portions of these bores being enlarged to receive the upper end portions of the casings for the cables. The end portions of the three cables remote from the members 92 are all connected to a single cam-actuated lever 114 pivoted at 116 (Fig. 4) and arranged to be actuated by an appropriately shaped cam surface 117 formed on the periphery of a cam 118 secured to a cam shaft 119 (Fig. 12). This cam surface is arranged to allow the members 92 to lower the rods 88 under the action of the springs 106 shortly after they have been moved upwardly partially to close the grippers since the upper jaws of the grippers will not return to their open position while the arms 76 lie at right angles to the surfaces 74 of the tail portions of the upper jaws. Such lowering of the rods 88 permits unhindered swinging movement of the side plates 80 carrying the arms 76 to close the grippers upon the upper materials.

The power-operated, cam-actuated mechanism for finally closing the upper jaws of the gripper upon the upper material comprises a wedge member 120 secured to the gripper-operating rod 64 and having faces 121, 122 at an obtuse angle to each other. The face 121 first cooperates with the rounded end of the block 99 carried by the side plates 80 to quickly move the gripper jaws to nearly closed position, the surfaces 122 then engaging the blocks 99 and finishing the closing movement at a slower rate and hence with greater gripping advantage. The lower ends of the gripper-operating rods 64 are connected by ball-and-socket joints to the upper end portions of links 123 the lower ends of which are all yieldingly connected to a block 130 (Fig. 1).

The block 130 is connected to a lever 132 fulcrumed at 133 on the frame. A rear arm of the lever 132 is connected by a link 134 to a lever 135 fulcrumed on the frame at 136 between its ends and carrying at one end a roll 136 which engages a cam path 140 formed in a cam 141 on the main shaft 119 (Fig. 12). The cam operates the lever 135 counterclockwise to draw down on the three grippers yieldingly through springs 142, 142.

Means for opening the toe-end gripper at a convenient stage in the machine cycle comprises a pair of parallel links 143 (Fig. 6) connected at their upper ends to a pair of levers 144 pivoted on a transverse horizontal stud 146 carried by side plates 80. The stud 146 lies above and slightly outwardly from the studs 78 and the levers 144 extend substantially forwardly in the machine, their connections to the links 143 being at their forward ends. On a stud 148 extending through transversely aligned holes in the side plates 80 between the levers 144 is pivotally mounted a roll 150 (Fig. 7), this roll being, when the jaws are closed, approximately half way between the studs 146 and 78. The roll 150 is adapted to engage the arm 76 on clockwise swinging of the levers 144 about their pivots 146 and to move the arm in a counterclockwise direction about its pivot stud 78. This movement of the arm moves the roll 75 away from the position it occupies when the grippers are closed, thus allowing the spring 84 to swing the upper jaw about its pivot to open the gripper jaws. Such swing-

ing of the levers 144 is effected by upward movement of the links 143.

The links 143 are pivotally connected at their lower ends to a yoke-like lever 152 pivoted on a shaft 154 extending horizontally widthwise of the machine and secured in a bore in the block 98, the block being received between the parallel arms of the yoke-like lever. The links 143 are connected to the rearwardly extending arms of the lever 152 which is also provided with a downwardly extending arm 156 having a hemispherical recess in a forward face, in which recess is received a ball 158 formed on the forward end of a rod 160 extending rearwardly of the machine through a bore in the arm 156 leading into said recess.

The rod 160 (Fig. 1) is pivoted to a lever 161 fulcrumed between its ends on a shaft 162 fixed on the machine frame, its lower arm carrying a roll 163. This roll is in the path of a cam 164 carried by a lever 165 fulcrumed at 166 on the frame and having a roll 167 engaging a cam path 168 in the cam 118 on the main shaft 119 (Fig. 12). When the lever 165 is moved counterclockwise by the cam path 168 in the cam 118, the cam 164 engages the roll 163 on the lever 161 and operates the lever to pull on the rod 160 to release the toe gripper. The lever 165 operates through a link 171, a lever 172 and a link 173 to raise and lower the wipers 52, as is to be more fully described later.

In the case of the side grippers, a finger 176 (Fig. 9) is pivotally mounted on the stud 71 forming the pivot of the upper jaw. The finger 176 has a second arm 178 extending beyond the stud 71 and adapted to engage a pin 180 projecting from one of the levers 144. Downward movement of the finger 176, on engagement thereof by the under surface of the wipers as they descend to perform their wiping action on the upper, may be effective to cause the arm 178 to engage the pin 180 on the lever 144 and cause the roll 150 carried thereby to swing the arm 76 from under the tail 72 of the upper jaw and allow the springs 84 to open the side gripper jaws. Should the side grippers be opened in this manner, the wedge members 128, which are then exerting a downward pull on the side grippers, will draw the grippers farther downward, but the gripper jaws having once been opened by the action of the wipers remain open during such further descent and exercise no further tensioning action on the upper.

Should the side grippers, in performing their upper-tensioning movement, have moved so far downwardly in the machine that the wipers in their downward movement do not contact the fingers 176, the jaws will be opened substantially at the time when the wipers reach the end of their descending movement and before they advance and close by upward movement of the links 143 associated with the side grippers, such upward movement being effected by means of cam-operated pull rods 182 (Fig. 9) which extend upwardly through substantially vertical bores in inwardly extending arms 184 projecting from yoke-like levers 186 which are coupled to the links 143 of the side grippers and are pivotally mounted on the blocks 98. The rods 182 at their lower ends are pivoted to the front arms 188 of levers (Fig. 1) fulcrumed between their ends on a shaft 190 fixed in the frame. The rear arms 192 of the levers are pivoted to a link 194 the upper end of which is pivoted at 196 to one arm of an angle lever 198 fulcrumed at 200 on the

frame. The other arm of the angle lever carries a roll 202 which engages a cam path 204 in a cam 206 on the main shaft 119. The cam path 204 is designed to move the angle lever clockwise to release the side grippers at about the time the wipers have finished their downward and wiping movements.

The means for causing upward movement of the central portion of the shoe support and for causing the toe-end gripper to close upon the upper is generally similar to that described in the application referred to above. However, latch members 207, 208 associated with the shoe-support mechanism and the toe-end grippers respectively are, in the present machine, automatically released. As shown in Fig. 1, a lever pivoted on the shaft 190 has an arm 210 carrying a roll seated in the track 204 of the cam 206, the lever having an arm 212 connected by a link 214 to an arm 216 pivoted on the shaft 133 and to which a latch-releasing bar 218 is pivoted. At the proper time in the cycle, sufficient clockwise rotation is imparted to the lever 210, 212 by the cam track 204 to cause the bar 218 to release first the latch 207 to cause the central portion of the work support to rise and then the latch 208 to permit the rod 128 to be drawn down by the springs 142 to cause the toe gripper to grip and pull the upper.

The central portion of the work support is carried by a vertical sliding post 222 (Fig. 6) on the lower portion 224 of which is a pin 226. This pin is engaged by a vertically sliding member 228 (Fig. 5) which has a roll 230 resting on a cam plate 232. The plate is fixed to a shaft 234 on which is an arm pivotally connected by a link 238 to an arm 240 on an angle lever pivoted at 242 on the post 69. The other arm 244 of the angle lever carries a hardened block 245 which overlies the upper end of the latch 207. A tension spring 248 is connected between a pin 250 on the arm 240 and a pin 252 on the post 69 so that when the latch 207 releases the arm 244 the spring 248 will rotate the cam plate 232 and raise the central portion of the work support.

In the illustrated machine, the heightwise position of the central portion 258 of the work support is made adjustable in order that the angle formed between the upper surfaces of soles of different thicknesses and the sides of the last may be positioned at the desired height relative to the wipers irrespective of the thickness of the sole being operated upon. The central portion 258 (Fig. 6) of the shoe support is pivotally mounted on a transverse pin 260 carried by the upper portion 222 of the post whose lower portion 224 is engaged by the vertically sliding member 228. The upper portion 222 of the post is adjustable relatively to the lower portion 224 by means of a screw 264 threaded into a longitudinal bore 265 in the upper portion 222 and having its head seated in the lower portion 224. Relative rotation of the two portions is prevented by means of an upstanding lug 266 on the lower portion which engages a recess 268 in the upper portion. By removing the upper portion of the post in the machine and adjusting the setting of the screw 264, then replacing the upper portion of the post, the heightwise position of the central portion of the shoe support may be readily adjusted. The bore 265 extends upwardly throughout the length of the upper portion 222 of the post but only the lower end portion of the bore is threaded. The setting of the screw 264 in the bore 265 is frictionally maintained by engagement of the up-

per end of the screw with the lower surface of a friction member 270 on which is seated the lower end of a compression spring 272 in the bore. The upper end of the spring engages the lower end of a plunger 274 the upper end portion of which projects beyond the upper end of the post and engages a machined surface 276 on the under side of a pivoted bar 278 forming part of the central portion 258 of the work support. The plunger 274 engages the bar 278 more or less directly below the pivot 260 for the bar and is effective to retain the central portion of the shoe support in its operative position about its pivot and minimizes any tendency for that portion to be tipped upward about its pivot 260 on the post 222. When the operator wishes to remove an outer portion 280 of the work support, the central portion 258 may be turned about the pivot 260 into an upright position where it will be retained by the plunger 274.

In the operation of the machine on a shoe, it has been found desirable to effect foredraw movement of the toe-end gripper, which movement will be substantially independent of the amount of downward upper-tensioning movement thereof. The amount of the downward movement will depend upon the amount of looseness of the upper upon the last and upon the stretchability of the upper materials. Furthermore, it has been found desirable for this foredraw movement to occur after the side grippers have moved downwardly somewhat with a view to achieving the result that the side grippers will be imparting sufficient tension to the upper to hold the last stationary on the shoe support against any tendency to tip about a toeward sole-engaging stud 282 of the shoe support when the foredraw movement is applied to the toe-end gripper.

In the illustrated machine, the foredraw mechanism (Fig. 6) comprises a roll 294 arranged to engage a substantially vertical surface 296 on the forward face of the toe-end gripper casing 62, said roll being pivoted on a horizontal pin 298. The pin is received in upwardly extending ears on the forward portion of a lever 302 which has parallel portions disposed one on each side of the toe-end gripper casing and extending rearwardly in the machine. The lever 302 is pivoted to the bracket 67 attached to the post 69 by means of pins 304 which extend through bores in the depending ears formed substantially midway of the lever. The pins 66 which secure the sleeve 65 to the bracket 67 lie some distance below the pins 304 and parallel thereto. The sleeve 65 turns on the pin 66 when foredraw movement is imparted to the gripper by the roll 294 and the gripper is normally held forwardly in the machine by the action of a spring 306 connected between the sleeve 65 and the bracket 67. To impart foredraw movement to the gripper against the action of the spring 306, the lever 302 is swung in a rearward direction about its pivot pins 304 by lengthwise movement of a downwardly and rearwardly extending link 308 made adjustable for length and pivoted at its upper end to the rear end of the lever 302 and at its lower end to a cam-actuated lever 310. This lever is pivoted on the shaft 162 and is actuated to impart foredraw movement to the gripper after the latter has moved downwardly an appreciable amount by a cam surface 314 formed on the periphery of the cam 118 on the cam shaft 119.

In the manufacture of inexpensive stitchdown shoes it is the practice with some manufacturers to employ an unlimited upper the toe portion of

which comprises an outer layer of material, for example leather, and a toe stiffener but no lining. In making such shoes it is common practice to use stiffeners of a given length and width in shoes the uppers of which are of different sizes. Thus, while the toe of the stiffener material may lie in suitable registration with the toe end of the outer layer, at the side portions of the toe, portions of the surplus stiffener material may project outwardly from beneath the edges of the outer layer.

When a toe-shaping operation is to be performed on such a shoe, the outwardly projecting surplus portions of stiffener material will usually be in a sticky condition and such portions will tend to adhere to the lower jaws of the side grippers when the latter are opened to permit the wipers to perform their operation on the shoe. Such adhesion may be sufficient to tear away partially the surplus portions from the remainder of the toe stiffener and, when the grippers are subsequently returned to their initial positions and the shoe is removed from the machine, may cause at least partial loss of the shaping effects previously produced on the upper since the adhesion of the surplus portions to the lower jaws will be likely to cause displacement of the outflanged margin of the upper material adjacent to the crease at the opposite sides of the shoe. To avoid this, means is provided for forcibly dislodging any such portions of the stiffener material which may adhere to the side grippers.

Each stripping device (Fig. 9) comprises a member having a crossbar 350 lying just outward of, and at least substantially parallel to, the outer edge of the lower jaw of the side gripper with which it is associated. The crossbar 350 is provided with outwardly extending ears 352 by which it is freely pivoted on the stud 71 forming the pivot of the upper jaws of the side grippers. Extending inwardly from the crossbar 350 is a plurality (for example five) of relatively fine prongs 354 arranged somewhat like the teeth of a comb, the prongs as seen in plan (Fig. 4) being substantially perpendicular to the adjacent portion of the outer edge of the lower jaw which they overlie. The prongs extend across the width of the jaw and, when the gripper is closed, three of the prongs lie in grooves 356 cut in the gripping faces of the jaw 60 and extend across its inner end. The prongs underlie the margin of the upper gripped by the jaws but do not interfere with the normal gripping action of the jaws upon the upper.

The prongs 354 remain in their raised position, as shown in Fig. 9, while the machine is inoperative and, in order to prevent upper material from entering the space between the lower sides of the prongs and the lower jaw, the free ends of the prongs are turned down to shroud the space between them and the lower jaw of the gripper, the downturned ends, when the jaws are closed, entering the grooves in the end portion of the gripper jaw. Toward the end of a cycle of operations of the machine, when the grippers are returned to their initial positions (the jaws having been previously opened as hereinbefore described), the prongs of each stripping device are forcibly urged upward out of the grooves in the lower jaw by the engagement with the crossbar 350 of a projection 358 extending upwardly from the upper end of the wedge member 120 associated with the gripper-operating mechanism. The projection 358 extends upwardly through an opening in the gripper casing and engages the crossbar 350 when the wedge member 120 is

11

moved upwardly to return the grippers to their initial position. The upward movement of the prongs out of their groove will forcibly detach from the lower gripper jaw any of the stiffener material which may then be adhering thereto.

When a shoe has been correctly presented to the machine with the margin of its upper projecting over the two stripping devices of the side grippers and the operator starts the machine into operation, the consequent downward movement of the two wedge members 120 associated with the side grippers will allow the two stripping devices to move downwardly about their pivots 71 until the prongs are received within the grooves 356 in the lower jaws 60 of the grippers.

In using a machine organized as described in the application referred to above, it has been found that movement of the heel-end abutment 56 into engagement with the heel end of the shoe tends to cause the last to be displaced in the toeward direction so that its lower beveled face tends to override the upper surface of the toe-positioning fingers 58. In order to minimize such tendency, in the illustrated machine, the movement of the heel-end abutment is delayed until the grippers have moved to exert some tension on the toe-end portion of the upper, such tension being effective to hold down the toe-end portion of the last and minimizing any tendency thereof to override the upper surface of the fingers.

A post 360 (Fig. 1) which carries the heel abutment 56 has pivoted to it at 362 an adjustable arm 364 the lower side of which has rack teeth engaging a pinion 366 on a shaft journaled in the machine frame. On this shaft is a ratchet wheel 398 on the hub of which is wound a cable 370 held under tension by a spring 372. On a fixed shaft 374 a lever 376 is fulcrumed between its ends, the upper arm of the lever being curved forwardly to engage the end of the arm 364 and the lower arm being connected by a rod 378 to a lever 380 fulcrumed on the shaft 166 and having at its lower end a roll which engages a cam path 382 in the cam 206. After the grippers have seized and pulled the upper, the cam path 382 allows the lever 380 to release its pull on the rod 378, the lever then turning clockwise and allowing the spring 372 to move the abutments 56 into shoe-engaging position. The lever 376 carries a pawl 384 which finally engages the ratchet wheel 368 and locks the abutment 56 in shoe-engaging position.

In order further to minimize the risk of the toe end of the last riding up over the surfaces of the positioning fingers 58, particularly when the shoe is being presented to the machine, these fingers are provided with two last-engaging surfaces (Fig. 3), one 386 of these surfaces being adapted to engage the beveled face of the last and the other surface 387 formed on an upwardly projecting portion of the finger being adapted to engage the surface of the last immediately above the beveled face referred to above. The construction is such that, as the last is placed into engagement with the fingers, the surfaces 387 serve to prevent the beveled face of the last from overriding the fingers.

In the illustrated machine, the return of the fingers 58 from their retracted position to their operative last-engaging position is delayed as compared with the corresponding movements in the machine disclosed in the above-mentioned application. By delaying their return to as late

12

a stage as possible, the operator is given more time to remove the shoe from the machine before the fingers return to their operative position, thus preventing engagement of the fingers with the upper after the shaping operation.

The wipers 52 are carried by a wiper-carrying casting 388 (Fig. 1) which is moved forward into operative position with respect to the shoe by depression of a treadle 390 which pulls on a link 392 to move clockwise an angle lever having three arms 394, 395, 396, the link 392 being connected to the arm 394. The arm 395 pulls on a rod 398 connected to a lever 400 pivoted on the frame at 402 and having an arm 404 which, with a link 406, constitutes a toggle straightening of which by the pull on the rod 398 moves the wiper-carrying casting 388 into operative position. The toggle 404, 406 is automatically broken to allow the wipers to be retracted by a spring 408 when, near the end of the cycle, the lever 132 is operated to raise the grippers. For this purpose an arm 410 is pivoted on the shaft 133 and is held by a spring 412 against an abutment on the lever 132. When the lever 132 moves clockwise to raise the grippers, the arm 410 strikes the third arm 396 of the angle lever and pushes on the rod 398 to break the toggle.

The wiper-carrying casting 388 has a sliding connection at 414 with a block 416 pivoted at 418 to the frame. The block is connected at 420 with the link 173 which is operated as described by the cam lever 165 which raises and lowers the wipers. The block 416 carries a rearwardly extending arm 422 connected by a link 424 to an arm 426 on a rockshaft 428, the arm being moved clockwise as the wipers descend. On the shaft 428 is a similar arm connected to a rod 430 which has (Fig. 2) a bifurcated upper end embracing a center pivot pin 432 of a toggle comprising links 434, 436. The forward link 434 is pivoted to a slide 438, and the rear end of the link 436 is pivoted on a shaft 440 journaled in a casting 442 which carries pins 441 (Fig. 1) journaled in the frame 42. The casting carries the shoe-positioning fingers 58 and its forward end is supported by a spring plunger 444. The rear link 436 of the toggle is provided with a tail portion 446 which depends below the pivot 440. The tail portion is engaged by a spring-pressed plunger 448 which is received in a rearwardly extending bore in the slide 438 and which acts to urge the toggle into its straightened position which is determined by engagement of an abutment 450 on the link 436 with the slide.

When the wipers are moved downwardly during the operation of the machine on a shoe, the rod 430 is moved upwardly to engage the pin 432 at the joint of the toggle 434, 436 and lift it to break the toggle against the action of the spring plunger 448. Thus the breaking of the toggle withdraws the slide 438 to which the shoe-positioning fingers 58 are connected.

When the toggle 434, 436 has been broken, a latch member 452 which extends up from a transverse horizontal pin 454 by which it is pivoted to the slide 438 is swung by the action of a spring-pressed poppet 456 forwardly until a projection 458 on the latch moves under the pin 432 and prevents downward movement of the pin when the rod 430 is lowered as the wipers are raised after they have performed their wiping operation.

When, toward the end of the fourth stage of the cycle of the machine the grippers are raised and the toggle 404, 406 automatically broken, the wiper-carrying casting 388 is retracted by the

Spring 408 and as it moves rearwardly a collar 460 adjustably mounted on a wiper-closing rod 462 engages the latch 452 and moves it rearwardly, thus releasing the toggle 434, 436 and allowing the spring plunger 448 to straighten the toggle and restore the shoe-positioning fingers 58 to their operative positions.

Usually the right-hand head of the machine will be adjusted for operation on the right shoe of a pair and the left-hand head for operation on the left shoe of the pair. Such adjustments include moving the shoe-positioning fingers 58 toward and from each other to accommodate shoes of different widths and swinging the fingers bodily to the right or left of the center line of the head to accommodate lasts with different degrees of swing or different styles of toe. To facilitate the adjustment of the positioning fingers of one head to correspond with those of the other head, novel means is provided comprising scales and pointers so that the adjustment of the fingers of one head may be read off and the other head adjusted to correspond.

Each head of the machine is provided with the following mechanism. A rod 464 (Fig. 4) is threaded into blocks 468, 469, the part of the thread in one block being a right-hand thread and the part in the other block being a left-hand thread. The blocks are pivoted to angle levers 470 which are connected by links 472 to the shoe-positioning fingers 58 which occupy arcuate grooves 474 in the casting 442. Rotation of the rod 464 will thus move the fingers 58 along their grooves toward and from each other. A sleeve 476 is concentric with the rod 464 and has a left-hand end portion threaded into the slide 438. The rod 464 is freely rotatable within the sleeve 476 and is held against axial movement relatively thereto. Rotation of the sleeve therefore displaces the rod 464 laterally in the machine to swing the bell-crank levers 470 in the same direction about their pivots to offset the fingers 58 with respect to the center line of the head of the machine with which they are associated. The sleeve 476 is freely rotatable within a block 478 and is held against axial movement relatively thereto by engagement of one end of the block with a flange 479 on the sleeve and by engagement of the other end of the block by a thumb head 480 by which the sleeve may be rotated. Secured in slightly spaced relation to the under side of the block is a rearwardly extending plate 482 having an arcuate rear edge. This edge is concentric with the axis of a pivot pin 484 which extends through a bore in the block 478. A pointer 486 is pivoted on the pin 484 below the plate 482, and another pointer 488 is pivoted on the same pin and lies above the plate. The pointer 486 extends rearwardly and has a pointed end portion which is bent up and over the arcuate edge of the plate so that its end lies above a scale 490 on the plate. The pointer 488 also extends rearwardly and has a pointed end portion which lies over a scale 491. The pointer 486 has a forwardly extending arm 492 having a short stud 493 which is connected by a rigid wire link 494 with the slide 438. The other pointer 488 is provided with a stud 496 extending upwardly at the rear of the block 478 and pivotally connected at its upper end by means of a link 497 to the upper end portion of the pin 484. The stud 496 is connected by means of a rigid wire link 498 to the block 469.

When the rod 464 is rotated by its thumb head 500 the pointer 488 moves over the scale 491 and

when the sleeve 476 is rotated by its thumb head 480 the pointer 486 moves over the scale 490. The scale 491 is conveniently provided with graduations identified by consecutive numerals starting at one edge of the plate and the scale 490 has conveniently a center zero with equally spaced graduations identified with consecutive numerals increasing outwardly from the center of the scale, the numerals on one side being identified by the letter L and the numerals on the other side by the letter R.

A brief description of the operation of the machine in the successive stages of a complete cycle follows.

15 The wipers 52, grippers 46, 48 and 50, vamp-pressing member 54, toe-and-positioning fingers 58 and the shoe-supporting devices 56 of the illustrated machine occupy the positions shown in Fig. 1 when the machine is at rest ready to commence the cycle of operations. In the illustrated machine, however, the upper jaw of each of the three grippers will be widely open to permit the upper to be easily placed between the jaws. The prongs 354 of the stripping devices for the two side grippers will at this time be raised above the work-engaging faces of the lower jaws.

20 Before presenting a shoe to the machine, the operator will satisfy himself that the wipers 52 fitted to the machine are of the correct shape for the work in hand and that they are properly adjusted in the machine to operate satisfactorily upon the work.

25 The operator will then present a shoe, say a right shoe, to the right-hand head of the machine with the toe-end portion of the upper turned back so that he has a clear view of the toe end of the last and of the toe-end-positioning fingers 58. He will then, if necessary, adjust the position of these fingers by rotation of the thumb heads 480 and 500 until they properly position the toe-end portion of the last in the machine. The operator may then read off the positions of the pointers as indicated on the scales 490, 491 and similarly adjust the pointers on the other head of the machine so that they will correctly position the toe end of the last for a left shoe of the same pair.

30 The operator will ensure that the grippers are correctly positioned for operation on the shoe to be presented and that the heel abutment 56 is correctly adjusted. He will further take care that the heightwise position of the central portion 258 of the shoe-supporting device is correct by appropriate adjustment of the screw 264 projecting from the upper portion 222 of the post.

35 Having prepared the machine for operation on the shoe, the operator smooths the toe portion of the upper downwardly into its previously contacting relation with the last. At this time the central portion 258 of the shoe-supporting device occupies a somewhat lowered position in the machine, thus facilitating the introduction of the toe end of the sole beneath the inner edges of the lower jaws of the grippers. The toe end 45 of the last is held in engagement with the toe-end-positioning fingers 58, the last-engaging surfaces 385, 387 of which engage respectively the bevel and end face of the last, thus minimizing any tendency for the last to override the fingers.

40 The fact that the gripper jaws are widely open facilitates the introduction of the upper materials into position to be grasped by the jaws.

45 The operator will now depress a clutch-engaging treadle 504 which initiates the first stage of the cycle of operations. During this stage

which occupies some 20° of revolution of the cam shaft 119, the cam surface 117, through the mechanism described, pulls on the cables 100 of the auxiliary gripper-actuating mechanism partially to close the jaws of the grippers and then releases tension on the cables. The cam path 168, through the mechanism described, operates the latch-releasing member 218 to release the latch member 207 holding the central portion of the shoe-supporting device in lowered position. This allows the spring 249 to raise the central portion 258 to sole-engaging and shoe-supporting position. Further movement of the member 218 releases the latch 208 and allows the updraw springs 142 associated with the toe-end gripper to close that gripper upon the upper but no tensioning movement of the gripper occurs at this time. The machine is then brought to rest automatically by the clutch mechanism.

If the operator is satisfied with the positioning of the shoe, he will then initiate the second stage of the cycle by again depressing the clutch-actuating treadle 504. During this stage the cam track 140, through the mechanism described, causes the toe-end gripper to commence its tensioning movement by drawing that gripper downwardly in the machine while the side grippers close upon the upper and then move downwardly, outwardly and towardly to tension the upper. After the side grippers have moved to apply some degree of tension to the upper, the heel-end abutment 56 is allowed by the cam path 382 to be moved into engagement with the heel end of the shoe and to be locked in that position, and the cam surface 314 acts through the mechanism described to initiate the foredraw movement of the toe-end gripper by moving that gripper rearwardly in the machine to apply a foredraft to the upper which is substantially independent of the downward movement of the gripper. The machine is automatically brought to rest at the end of the second stage by the clutch mechanism, the cam shaft 119 having by this time completed about one-fifth of a revolution. While the grippers are tensioning the upper the operator inspects the upper and makes any necessary adjustments of the tension applied by any of the grippers, as described in the above-mentioned application, after which he will depress the wiper-controlling treadle 399, which movement straightens the toggle 404, 406 to move the wipers 52 and vamp-pressing member 54 into operative position, and he then operates the clutch-actuating treadle 504 to initiate the third stage of the cycle of operations.

This third stage corresponds to the second stage of the operation of the machine disclosed in the above-mentioned application in which, as in the present machine, the periphery of the shoe support is raised by a cam path 506 in the left-hand face of the cam 118. The wipers 52 are advanced by the cam track 508 in the right-hand face of the cam 118. The wipers are closed by a cam track 510 in the right-hand face of the cam 206. In the illustrated machine, however, the toe-end gripper is further operated in the third stage of the machine to foredraw the upper, and the toe-end gripper is opened as a result of upward movement of the links 143 associated therewith by the movement of the cam lever 165 to depress the wipers. The side grippers will be opened by engagement of the gripper-releasing fingers 176 by the wipers of the grippers have not descended sufficiently far in the machine to lower the fingers out of the path of the downward

movement of the wipers or, if this is the case, the side grippers will be opened by the power-operated cam 206 the cam path 204 of which operates as already described to release the side grippers.

5 In the illustrated machine it will be noted that once the arms 16 have been moved out of the positions in which they are at right angles to the under surfaces 12 of the tail portions 70 of the upper jaws of the grippers, the jaws are held open 10 by the springs 84. At the end of the third stage of the cycle of operations the grippers occupy lowered and opened positions, while the wipers 52 and the surrounding portion 280 of the shoe-supporting device are operating to cause a semi-permanent set to be imparted to the outwardly 15 extending flange of the upper which overlies the margin of the sole then engaged by said surrounding portion of the shoe-supporting device. After the lapse of sufficient time for such a set 20 to be imparted to the flange of the upper, during which time the operator may conveniently place the other shoe of the pair in the other head of the machine, the operator will initiate the fourth and final stage of the cycle of operations of the 25 first head, during which stage the operating instrumentalities are returned to their initial positions except that, in the illustrated machine, as the grippers reach their initial positions, the stripping devices 350 of the side grippers will be 30 forcibly raised to remove any material tending to adhere to the lower jaws of the grippers so as to facilitate removal of the shoe from the machine.

Furthermore, the return of the toe-end-positioning fingers to their initial positions is prevented by the latch member 452 which retains the toggle 434, 436 in broken condition until the wiper-carrying casting 388 is moved rearwardly in the machine, whereupon as the wipers complete their rearward movement the collar 460 engages the latch 452, allowing the toggle to straighten and restore the shoe-positioning fingers to their operative positions. This delay in the return of the toe-end-positioning fingers to operative position gives the operator more time 45 in which to remove the shoe from the machine before the return of the fingers, thus minimizing the possibility of their engaging the edge of the flanged portion of the shoe upper and moving it from the neighboring portion of the sole.

50 The cam shaft 119 is brought to rest automatically at the end of the cycle of operations of the machine by the clutch mechanism, with the various instrumentalities ready to operate upon a shoe of the next pair.

Having thus described my invention, what I claim as new and desire to secure by Letters Patent of the United States is:

1. In a machine for working uppers over lasts, a gripper having its jaws widely open, power-operated means for partially closing the gripper jaws, means for closing the gripper jaws upon the upper, and means for operating the gripper to pull the upper.

2. In a machine for working uppers over lasts, a gripper having its jaws widely open, means for moving one jaw toward the other partially to close the gripper jaws, and power-operated means for continuing such movement to close the gripper jaws upon the upper and to pull the upper.

3. In a machine for working uppers over lasts, a gripper having its jaws widely open, power-operated means for partially closing the gripper jaws, and power-operated means for closing the gripper jaws upon the upper and for pulling the upper,

4. In a machine for working uppers over lasts, a gripper having a lower jaw, an upper jaw connected to the lower jaw by a pivot and having a tail extending beyond the pivot, a pivoted strut, means for swinging the strut to engage the tail and partly to close the jaws, means for turning the upper jaw and strut about the pivot of the jaw to close the jaws upon the upper, and means for moving the jaws bodily to tension the upper.

5. In a machine for working uppers over lasts, a lower jaw, an upper jaw connected to the lower jaw by a pivot and having a tail extending beyond the pivot, a pivoted strut having a projection, a rod movable lengthwise to engage said projection and move the strut against the tail of the jaw partially to close the gripper, a semicircular member pivoted at the center of curvature and pivoted to said rod, a cable attached to said member to lie along its periphery, and power-operated means for pulling on the cable to operate the strut.

6. In a machine for working uppers over lasts, a gripper comprising upper and lower jaws pivoted together, the upper jaw having a tail extending beyond the pivot, a pivoted strut having a projection, a rod movable lengthwise to engage said projection to move the strut against the tail of the jaw partially to close the gripper and to locate the strut substantially at right angles to the tail, a semicircular member pivoted at the center of its curvature and pivoted to said rod, a cable attached to said member to lie along its periphery, and power-operated means to pull upon the cable to operate the strut.

7. In a machine for working uppers over lasts, a gripper having a lower jaw, an upper jaw connected to the lower jaw by a pivot and having a tail extending beyond the pivot, a strut, a pivot therefor, means for swinging the strut to engage the tail and partly close the jaws, means for arresting the movement of the strut when it is just beyond a position at right angles to the tail, means for turning the upper jaw and the strut about the pivot of the jaws to close the jaws upon the upper, and means for moving the jaws bodily to tension the upper.

8. In a machine for working uppers over lasts, an upper-tensioning gripper comprising a casing, a lower jaw fixed to the gripper casing, an upper jaw connected to the gripper casing by a pivot and having a tail, side plates mounted to turn on said pivot, a strut mounted on a pivot between the side plates and movable to engage said tail partially to close the jaws, a block between the side plates, a movable wedge member engaging said block, and means for moving the wedge member to turn the side plates about their pivot to complete closing of the jaws and to move the gripper bodily to pull the upper.

9. In a machine for operating upon shoes, an upper-tensioning gripper, means for opening and closing the jaws of the gripper to seize and release the upper, and means associated with a jaw of the gripper for releasing the upper should it adhere to the jaw when the jaws are opened.

10. In a machine for operating upon shoes, an upper-tensioning gripper comprising upper and lower jaws, means for opening and closing the jaws to seize and release the upper, upper freeing means associated with that jaw of the gripper which engages the inner side of the upper, said means being operated by the gripper-opening means to strip the upper from said jaw.

11. In a machine for operating upon shoes, a pair of pivoted jaws for seizing an upper, a bar

movable about the pivot of the jaws, prongs carried by the bar and normally lying in recesses in one of the jaws, and means for engaging the bar when the jaws are opened to lift the prongs out of the recesses and strip the upper from that jaw.

12. In a machine for operating upon shoes, an upper-tensioning gripper, means for opening and closing the jaws of the gripper to seize and release the upper, a comb-like member associated with a jaw of the gripper, the prongs of the comb, being recessed in the gripping surfaces of the jaw, and means operated by the means for opening the jaws for lifting the comb-like member to free the upper from the gripping face of the jaw.

13. In a machine for operating upon shoes, an upper-tensioning gripper comprising pivoted upper and lower jaws, means for operating the jaws to seize and release the upper, a bar extending across one of the gripping jaws between its gripping face and its pivot, prongs secured to the bar and extending across the gripping face of the gripper, the jaws having recesses to permit the prongs to be normally below the gripping face, and means for lifting the bar when the jaws are opened to free the upper from the gripping face of the jaw.

14. In a machine for operating upon shoes, a gripper having a pair of pivoted jaws for seizing an upper, a bar movable about the pivot of the jaws, prongs carried by the bar and normally lying in recesses in the jaws, the ends of the prongs being turned down to shroud the space between the jaw and the prongs when the prongs are raised, and means for engaging the bar when the jaws are opened to lift the prongs out of the recesses and strip the upper from the jaw.

15. In a machine for working an upper over a last, a support for engaging the shoe bottom, last-positioning fingers movable into and out of operative position to locate the last upon the support, upper-tensioning means, wipers movable into and out of operative position over the toe of the shoe and heightwise thereof to wipe the tensioned upper, means for retracting the shoe-positioning fingers during the wiping operation, means for holding the fingers in retracted position, and means for releasing said holding means when the wipers are withdrawn from operative position over the shoe.

16. In a machine for working an upper over a last, a support for engaging a shoe bottom, last-positioning fingers movable into and out of operative position to locate the last upon the shoe support, upper-tensioning means, wipers movable into and out of operative position over the toe of the shoe and movable heightwise thereof to wipe the tensioned upper, means for retracting the shoe-positioning fingers operated during the heightwise movement of the wipers, a latch for holding the fingers in retracted position, and means for releasing the latch when the wipers reach their inoperative position.

17. In a machine for working an upper over a last, a support for engaging the shoe bottom, last-positioning fingers movable into and out of operative position to locate the last upon the support, upper-tensioning means, wipers, a wiper-carrying head movable into and out of operative position over the toe of the shoe and heightwise thereof to cause the wipers to wipe the tensioned upper toward the shoe bottom, a toggle connected to the shoe-positioning fingers, means operated during heightwise movement of the wipers for bending the toggle to retract the shoe-positioning fin-

75

gers, a latch for holding the toggle in bent position, and means on the wiper-carrying head to engage the latch when the wiper-carrying head reaches its withdrawn position from over the shoe.

18. In a machine for working an upper over a last, a shoe support, shoe-positioning fingers for locating the shoe upon said support, means for moving the fingers toward and from each other to locate lasts of different sizes, means for moving the fingers bodily laterally of the shoe support to locate lasts of different swing, a scale and pointer for indicating the amount of movement of the fingers toward and from each other, and a scale and pointer for indicating the amount of bodily lateral movement of the fingers to the right or left.

19. In a machine for working an upper over a last, a shoe support, shoe-positioning fingers for locating the shoe upon the support, means including a right- and left-hand threaded screw for moving the fingers toward and from each other to locate lasts of different sizes, means including a threaded sleeve concentric with the screw for moving the fingers bodily laterally of the shoe support to locate lasts of different swing, a scale, a pointer operated by rotation of the screw for indicating the amount of movement of the fingers toward and from each other, a second scale, and a second pointer operated by rotation of the sleeve for indicating the amount of bodily lateral movement of the fingers to the right or left.

20. In a machine for working an upper over a last, a shoe support to support the upper right side up, an abutment to engage the rear end portion of the shoe, a pair of shoe-positioning fingers engaging the end face of the toe portion of the last, means for varying the spacing of the fingers from each other, means for tensioning the upper to hold the shoe down on the support and in engagement with the fingers, and means acting after the upper is so tensioned for moving the abutment into contact with the rear portion of the last and locking it in shoe-holding position.

21. In a machine for operating on a stitchdown shoe having an upper loosely mounted on a last the bottom of which is beveled and an extension sole attached to the last, a support for the shoe sole, an abutment movable to engage the rear-end portion of the shoe, positioning fingers engaging the toe portion of the last both on its end face and on the beveled portion, means for tensioning the upper heightwise of the last, and means operating after the upper has been placed under tension for moving the abutment into engagement with the shoe and holding it against said fingers.

22. In a machine for working an upper over a last, a support to hold an upper on its last right side up, an initially retracted abutment to engage the rear portion of a shoe, means urging the abutment toward the shoe, a pair of shoe-positioning fingers, each engaging the end face of the toe portion of the last and a surface on the bottom portion of the last, means for tensioning the

upper to hold the shoe down on the support and in engagement with the fingers, means acting automatically after the upper is so tensioned to permit the abutment to move into contact with the rear portion of the last, and means for locking the abutment in last-engaging position.

5 23. In a machine for working an upper over a last, a shoe support having a vertically movable center portion, a gripper for tensioning the toe portion of the upper, means including a tensioned spring for raising the center portion of the work support, a latch for preventing action of the spring, and means for automatically tripping the latch to cause the center portion of the work support to be raised by its spring when the machine begins its operation.

10 24. In a machine for working an upper over a last, a shoe support having a vertically movable center portion, a gripper for tensioning the toe portion of the upper, means including a tensioned spring for raising the center portion of the work support, a latch for preventing action of the spring, means for automatically tripping the latch to cause the center portion of the work support to be raised by its spring when the machine begins its operation, and means including a screw for varying the heightwise position of the center portion of the shoe support.

15 25. In a machine for working an upper over a last, a shoe support, a gripper for tensioning the toe portion of the upper, spring means for closing the gripper and pulling the upper, a latch for preventing action of the spring means, and means for automatically tripping the latch to cause the grippers to grip the upper at an early stage in the operation of the machine.

20 26. In a machine for working an upper over a last, a shoe support having a vertically movable center portion, a gripper for tensioning the toe portion of the upper, spring means for closing the gripper and pulling the upper, means for automatically placing the spring means under tension, a first latch for preventing action of the spring means, means including a tensioned spring for raising the central portion of the work support, a second latch for preventing action of the spring, and power-operated means for first tripping the second latch to allow the central portion of the work support to be raised by its spring and then tripping the first latch to cause the gripper to grip the upper.
